GEORGE H. EMERSON AND HENRY YOERG, OF ST. PAUL, MINNESOTA, ASSIGNEES TO
LOCOMOTIVE SUPERHEATER COMPANY, A CORPORATION OF DELAWARE.

SUPERHEATER.

1,105,623.

Specification of Letters Patent.

Patented Aug. 4, 1914.

Application filed January 20, 1909. Serial No. 473,235.

To all whom it may concern:

Be it known that we, GEORGE H. EMERSON and HENRY YOERG, of St. Paul, Ramsey county, Minnesota, have invented certain new and useful Improvements in Superheaters, of which the following is a specification.

Our invention relates to superheaters designed particularly for use on locomotives and located in the smoke box and boiler flues and arranged to receive the saturated steam from the dome and superheat it before delivery to the cylinders.

The object of our invention is to provide a superheater having comparatively few joints and connections and easily accessible for the purpose of removal or repairs.

A further object is to provide improved means for connecting the boiler flue superheater tubes with the main portion of the superheater.

Other objects of the invention will appear from the following detailed description.

The invention consists generally in various constructions and combinations all hereinafter described and particularly pointed out in the claims.

In the accompanying drawings, forming part of this specification, Figure 1, is a transverse, sectional view of a locomotive smoke box, looking toward the flue sheet of the boiler, showing our improved superheater in place therein. Fig. 2 is a sectional view on a line substantially at right angles to the section line of Fig. 1. Figs. 3 and 4 are detail, sectional views, showing the construction of the superheater. Figs. 5 and 6 are detail views, showing different ways of securing the flue coils in the wall of the superheater, Fig. 7 shows a modification of the arrangement of the superheater tubes in the boiler flues.

In the drawing, 2 represents a locomotive boiler having a flue sheet 3 and smoke box 4. The boiler is of ordinary construction provided with the usual flues 5.

6 represents a series of flues of greater diameter than the ordinary boiler flues to adapt them to receive the superheater tubes or coils, and suitably arranged in the flue sheet to accommodate the superheater tubes, and similar to the flues generally employed in connection with a boiler superheater.

7 represents the header or casting forming the body of the superheater. There are

preferably two of these headers, one on each side of the longitudinal axis of the boiler and connected at their upper ends through a T-coupling 8 with a steam supply pipe 9. Through this steam pipe the saturated steam is supplied to the superheater. The pipe is preferably located, as shown, above and near the flue sheet, and the T-coupling forms a direct connection between the steam supply pipe and the headers of the superheater. 60 We are able, therefore, to locate the upper ends of the headers in close proximity to the top of the flue sheet, and from this point the headers extend downwardly to the bottom of the boiler where they are connected directly to the cylinder steam chests. This arrangement of the headers extending directly from the T-coupling to the steam chests without the use of intermediate joints or parts, we regard as a very important 65 feature in an apparatus of this kind, as it not only simplifies the construction and installation of the superheater, but eliminates almost entirely the annoyance and expense incidental to superheaters as generally made 70 where the care of leaky joints soon becomes a considerable factor in the cost of operating the boiler. Furthermore, in case of removal, it is only necessary to disconnect the joint at the top and bottom of the headers and the 75 entire superheater may be entirely removed from its position in front of the flue sheet.

The superheater headers or sections are of the same construction and a description of one will be sufficient, the other header being 80 represented by the same reference numerals with the addition of the exponent "a." Suitable connections 10 unite the lower ends of the headers with the steam chests of the locomotive. 85

Within the header casting longitudinal steam chambers 11 and 12 are provided, separated by a longitudinal partition 11'. The chamber 11, called the saturated steam chamber, communicates at its upper end 100 with the steam supply pipe 9 and receives steam therefrom and conducts it to the lower end of the header. The lower end of the chamber 11 is closed, however, to the escape of steam. The chamber 12 is closed 105 at its upper end and communicates at its lower end with the cylinder steam chest, as indicated clearly in Fig. 3. The header is preferably provided with external webs 13 and 14 projecting therefrom on each side 110

and extending lengthwise of the header. These webs have transverse sockets 15 and 16 therein, adapted to receive the ends of the tubes 17 and the sockets 15 and 16 are connected respectively by passages 18 and 19 with the chambers 11 and 12. These sockets 15 and 16 form a series of external pockets on each side of the header, and, as plainly shown in Fig. 3 one pocket communicates with one chamber and the adjacent pocket on the same side of the header communicates with the other chamber, and when the ends of the tubes 17 are inserted into these pockets to conduct the steam from one chamber into the flues and out again to the other chamber, both ends of each tube will be located on the same side of the header and it will only be necessary in removing the tube from the flues to detach its ends from the pockets and this may be done and any one or all of the tubes drawn out of the flues and removed from the boiler without displacing in any way the superheater header. This construction results in a further and decided advantage, for we are able to remove any one of the superheater tubes without disturbing any of the other tubes. Generally in devices of this kind where removal of the tubes is possible without displacing the header, it is necessary to remove the outer tubes or those in front to make the tubes in the rear accessible, and if a rear tube only is leaking, several tubes which are perfectly tight must be detached before the leaky one can be reached, and then when the tubes are replaced in the flues all of them so disturbed may leak. With our construction, the additional labor of removing the tubes already tight to obtain access to others, and the danger of making a tight tube leaky by displacing it, will be entirely avoided. Each tube is accessible and removable independently of all the others and if one tube, or several of them, become leaky, the defective ones can be reached at once without disturbing the connections of the header or the tubes which need no attention.

The middle portion of the tube 17 is preferably bent into loops which are inserted into the larger flues of the boiler and, as shown in the drawings, we prefer to provide two loops in each flue, formed by carrying one end of the tube into the flue and out again, thus forming a bend in the tube, and extending it into the flue again and back to the header and attaching it to the adjacent pocket on the same side of the casting. The saturated steam from the pipe 9 will enter the chamber 11 and passing therefrom through the ports 18 to the receiving ends of the tubes, will be conducted thereby into and through the loops in the boiler flues. These loops, as usual in devices of this kind, will be exposed to the hot gases and products of combustion, and the saturated steam will

be dried and superheated during its passage through the tubes. After flowing through the loops, the steam will enter the pockets again and flowing through the ports 19 will enter the superheater steam chamber 70 12 and from thence will pass through the connection at the lower end of the superheater steam chamber to the steam chest. The opposite webs are similarly equipped and the tubes arranged therein in substantially the same manner, there being preferably in the form of superheater shown herein, four sets of tubes; one set or group on each side of the superheater headers, and as the ends of the tubes of each group are 80 located on the same side of the header to which they are connected, it is obviously a very simple operation to detach the tubes entirely from the header castings for substitution and repairs. 85

Various means may be devised for connecting the ends of the tubes to the walls of the pockets, but we prefer to roll the tube ends therein and provide plugs 20 in the walls of the webs opposite the tubes where 90 they can be conveniently reached from the front of the smoke box. To remove the tube it is only necessary to cut it off where it enters the web, remove the plugs opposite the ends of the tube and cut out the short pieces 95 in the web with a chisel or other suitable tool. When the ends of the new tube are inserted, a flue expander may be thrust into the web through the plug holes and the ends of the tube expanded or rolled until a tight 100 joint is formed. (See Fig. 4.) This can all be accomplished by inserting the looped end of the tube into its flue and then springing the tube slightly until its ends slip into the sockets in the wall of the web. Generally 105 in superheaters it is necessary to remove the entire casting, as the tubes are each connected to opposite sides thereof, and the removal of a tube from its flue is impossible without first detaching the header itself. 110

We do not regard the external pocket as an indispensable adjunct to the superheater header, but only as a convenient means for connecting the ends of the tube with both chambers on the same side of the header. 115

In Fig. 5, we have shown a modified means for securing the tubes in the wall of the superheater, which consists in providing lock nuts 21 on the ends of the tubes within their sockets in the webs of the superheating casting, and arranging bushings 22 between these nuts and the plugs 20. Premature movement of the lock nuts will thus be prevented. The bushings 22 have holes 23, in their walls, leading to the chambers 11 120 and 12. 125

In Fig. 6, we have shown another means for securing the tubes in the wall of the superheater, which consists in interiorly threading the socket of the web and provid- 130

ing a nut 23', exteriorly threaded, to fit the wall of the socket and contacting with the nut 21 on the end of the tube. The removable plug opposite the nut 23' permits access to the socket and to the end of the tube. This nut will make a steam tight joint, and, at the same time, is readily accessible to permit removal of the tube and insertion of the new one.

10 In Fig. 7, we have shown a modified arrangement of the tubes in the boiler flues, which consists, as shown, in providing a loop 24 extending within one flue and then carried into the next flue instead of having 15 all the loops in one flue as illustrated in Fig. 3.

Generally, in superheaters of this type, a large number of joints and connections are provided, which are of expensive construction and soon become leaky through the twisting and racking of the locomotive. In the apparatus, which we have provided, the number of joints employed is reduced to a minimum, the connections are simple 25 and easily accessible and can be easily reached for examination and repairs.

We claim as our invention:

1. In a boiler, the combination, with a flue sheet and flues and a steam supply pipe, of 30 a relatively narrow superheater header lying entirely to one side of said flues and extending from near the top of the flue sheet to the bottom thereof and having, further, saturated and superheated steam chambers arranged one in front of the other, the header being connected with the steam supply pipe at the top and with the engine cylinders at the bottom, and superheater elements within the flues and having all their ends joined 35 to the two header chambers on the same side thereof but entering said chambers from the rear, the ends of each element as they enter the header being arranged below one another in the order of contiguity of 40 the flues to which the elements belong, whereby separation of any one of said tube ends to said header and the removal of any one or more of said tubes is possible without displacement of said header, or of the 45 other tubes.

2. The combination, with a boiler, flue sheet and rows of flues and a pipe for the saturated steam supply, of relatively narrow superheater headers arranged one on 55 each side of the boiler between rows of flues and extending from the top to the bottom thereof in front of the flue sheet, the upper ends of said headers having a T-coupling connection with said steam supply pipe near 60 the top of said flue sheet and the lower ends of said headers having connections with the cylinders and steam chests near the bottom of said flue sheet, each header having further saturated and superheated steam chambers one in front of the other, and super-

heating elements within the flues, the element ends of the two rows of flues on opposite sides of a given header being joined to the two chambers thereof on the same side of the header as are the flues containing them but entering said chambers from the rear, whereby separation of any one of said tube ends to said header, and the removal of any one or more of said tubes is possible without displacement of said header, or of the other tubes.

3. The combination, with a locomotive smoke box and flue sheet and flues therefor, and a pipe for the saturated steam supply, of a superheater header arranged with in said box, a coupling connecting said header with said steam supply pipe, said header consisting of a single casting having a longitudinal partition dividing it into a compartment for saturated steam 85 and a compartment for superheated steam, said saturated steam compartment communicating through said coupling with said steam supply pipe, and said superheated steam compartment having a connection with the steam chest, and superheating tubes arranged in groups on each side of said header, the ends of the tubes of each group communicating with said chambers respectively on the same side of said header.

4. The combination, with a boiler flue sheet and flues and a saturated steam supply pipe, of superheater headers arranged one on each side of the longitudinal axis of 190 the boiler and near said flue sheet, the upper ends of said headers having a connection with said steam supply pipe, and the lower ends of said headers having connections with the cylinder steam chests, each header comprising an elongated casting having a compartment for saturated steam and a compartment for superheated steam, the former communicating with said steam supply pipe and the latter with the connections 195 leading to the steam chests, superheating tubes arranged in groups on each side of said headers, the tubes of each group being located one above another and each tube in a group having its ends connected respectively with said steam chambers.

5. In a boiler superheater, the combination of a header divided by a partition into an independent compartment for saturated steam and an independent compartment for 120 superheated steam and having a plurality of external pockets, some of said pockets on one side of said header communicating with said saturated steam compartment, and the remaining pockets on the same side of the 125 header communicating with said superheated steam compartment, and superheating tubes connected between said saturated and superheated steam pockets.

6. In a superheater for locomotive boil-

ers, the combination of a header divided by a longitudinal partition into independent compartments for saturated and superheated steam, and having an external longitudinally arranged web provided with a series of transverse pockets communicating alternately with said saturated and superheated steam compartments, and superheating tubes connecting the adjacent pockets in said web.

7. A superheater comprising, in combination, a header having steam chambers therein and external longitudinal webs on each side thereof, said webs having transverse pockets therein, and passages connecting some of the pockets in each web with one of said chambers, and the remaining pockets in said webs with the other chamber, and superheating tubes having their ends communicating with said chambers respectively through the pockets in the same web.

8. A superheater for steam boilers, comprising a header having a longitudinal partition dividing said header into separate saturated and superheated steam chambers, and a longitudinally extending boss at the side of said header adjoining an end of said partition, said boss being divided into compartments, alternate ones of said compartments communicating with said saturated and superheated steam chambers.

9. A superheater for steam boilers, comprising a header having a substantially central longitudinal partition dividing said header into separate saturated and superheated steam chambers and longitudinally extending bosses at the sides of said header adjacent the ends of said partition, said bosses being divided into compartments, alternate ones of said compartments communicating with said saturated and superheated steam chambers.

10. A superheater for steam boilers, comprising a header having a longitudinal partition dividing said header into separate saturated and superheated chambers, a longitudinally extending boss at the side of said header adjoining an end of said partition, said boss being divided into compartments, and a superheater pipe having its opposite ends connected with alternate compartments in said boss to form a communication between said saturated and superheated steam chambers, said boss being provided with a stoppered opening substantially opposite one of the ends of said superheater pipe.

11. A boiler containing two curved rows of enlarged fire flues arranged about a central group of small flues, in combination with a curved header arranged in front of and substantially between said rows of enlarged flues, having a substantially central longitudinal partition dividing said header into separate, saturated and superheated

steam compartments, longitudinally extending bosses at the sides of said header adjoining the ends of said partition, said bosses being divided into compartments communicating with said saturated and superheated steam chambers and superheating pipes occupying said enlarged fire flues and having their opposite ends connected respectively with said alternate chambers.

12. A boiler containing two curved rows of enlarged fire flues arranged about a central group of small flues in combination with a curved header arranged in front of and between said rows of enlarged flues, having saturated and superheated steam compartments, the former being connected with said boiler and the latter having an outlet, bosses on the side of said superheater having chambers alternately connected with said saturated and superheated steam compartments and superheating pipes occupying said enlarged fire flues and having their opposite ends connected respectively with said alternate chambers.

13. A superheater for a steam boiler, comprising, a header having a chamber connected with the saturated steam from said boiler, a chamber for superheated steam having an outlet, a pair of oppositely disposed longitudinal chambered bosses opening into said saturated and superheated steam chambers, and a superheating steam pipe having one end connected to a boss which communicates with the saturated steam chamber and the other end connected to the boss which communicates with the superheated steam chamber.

14. A superheater, comprising, a header, having longitudinally arranged saturated and superheated chambers therein and a series of ducts arranged in two rows on each side of said header and communicating with said chambers respectively, the ducts communicating with a chamber on a side of said header being staggered with respect to the ducts communicating with the other chamber on the same side, and superheater tubes communicating with said chambers on each side of said header through said ducts.

15. A superheater header having saturated and superheated steam chambers formed therein and external bosses formed on the side walls of said steam chambers and projecting laterally therefrom and having sockets communicating with said chambers respectively, the bosses communicating with one chamber being staggered with respect to those communicating with the other chamber for the same side of the header, and superheater tubes communicating with said chambers through said sockets.

16. A superheater comprising a header having longitudinally arranged saturated and superheated steam chambers therein and a series of bosses or lugs projecting

from the walls of said chambers on each side of said header, said bosses having sockets therein communicating with one of said chambers respectively, the bosses communicating with one chamber on one side of said header being staggered with respect to the bosses communicating with the other chamber on the same side, whereby all of the bosses on the same side will be exposed and accessible from the front of the header, and superheater tubes communicating with said chambers on each side of said header through said sockets.

17. A superheater comprising, in combination, a header having saturated and superheated steam chambers therein and two rows of external, longitudinally arranged bosses

on each side thereof, said bosses having transverse pockets therein, passages connecting the pockets in one row of bosses with one of said chambers and the pockets in the other row of bosses on the same side of the header with the other chamber, and superheating tubes having their ends communicating with said chambers respectively through the pockets on the same side of the header.

In witness whereof, we have hereunto set our hands this 11th day of January 1909.
